UNITED STATES PATENT OFFICE.

FRANK H. POEPPELMEIER, OF DAYTON, OHIO, ASSIGNEE OF ONE-FOURTH TO LAWRENCE A. POEPPELMEIER, ONE-FOURTH TO VINCENT E. POEPPELMEIER, AND ONE-FOURTH TO JOHN L. WEIGAND, ALL OF DAYTON, OHIO.

TYPE EJECTOR FOR COMPOSING MACHINES.

Application filed April 27, 1925. Serial No. 26,068.

This invention relates to new and useful improvements in type ejectors for composing machines.

It is the principal object of my invention 5 to provide for type composing machines, and more particularly those including a key-operated mechanism for setting type in a suitable form ready for printing, a simple and rapid type ejector which can be economically constructed and easily taken 10 apart for cleaning and repair.

It is another object of my invention to provide a device which will receive from the type chute of a composing machine, 15 multigraph as well as other standard type for the purpose of ejecting it laterally into a chase or individual tubes.

It is still a further object of my invention 20 to provide a device which will, without clogging the channels or breaking the type, receive and eject it at any rate up to 1300 a minute, which is far in excess of a keyboard operator's capacity at the present time. My device, capable of operation at 25 this excessive speed, eliminates all danger of type transposition which is so common in the slower operated machines.

Other important and incidental objects 30 will be brought out in the following specification and particularly set forth in the subjoined claims.

In the accompanying drawings, Figure 1 35 is a side elevational view of the ejector side of the device, partly in section, with the cover removed. Figure 2 is a top plan view of the device. Figure 3 is an elevational view of the ejector side of the device, showing the cover plate in place. Figure 4 is a 40 sectional view taken on the line 4-4 of Figure 1, showing the drive mechanism. Figure 5 is a perspective view of a multigraph type which is adapted to be ejected by my device. Figure 6 is an elevational view of the delivery end of the device. Figure 7 45 is a side elevational view of the drive mechanism and oscillating gears. And Figure 8 is a plan view of the inside of the ejector arm cover.

Referring to the accompanying drawings 50 for a detailed description of the form of embodiment of my invention illustrated therein, the numeral 1 designates a casting having a flat base 2 from which there projects upwardly a side support 3. Project-

ing upwardly from the middle portion of 55 the base 2, and integral with the side support 3, is a web 4 which is turned at its upper end to form a horizontal bearing 5 for a pulley shaft 6. (See Figures 4 and 6.) From this bearing 5 a web 7 inclines upwardly along the side support 3 with which it is integral, to a cylindrical boss 8 that forms a bearing for a transverse shaft 9 for a purpose to be hereinafter described. (See 60 Figures 2 and 7.)

Threaded on the inner end of the shaft 6 to promote ease of assembly, is a pulley 10 to receive a cable (not shown) by means of which the pulley may be driven from a suitable motor. Secured to the outer face of 70 the pulley 10 a short distance from its center, is a crank pin 11 to which a connecting rod 12 is pivotally attached. Fast on the transverse shaft 9 is a gear 13 to the outer face of which there is secured a disc 14 having a crank end to which the free end of the connecting rod 12 is pivotally secured by a pin 15. The throw of this connecting rod 12 is adjusted to oscillate the gear 13, 75 and through it the shaft 9, when the pulley 10 is rotated. (See Figure 7.)

Inclining sharply upward from the boss 8, and integral with the side support 3, is a web 16. Formed on the outer upper end of this web is a cylindrical boss 17 which forms a bearing for a transverse hinge pin 18 for a swinging yoke 19 that terminates at its lower end in a cylindrical boss 20 which forms a bearing for a transverse shaft 21. (See Figures 1, 2, 6 and 7.) Fast 90 on the inner end of the shaft 21 is a gear 22 which meshes with the gear 13 for oscillation by it. The gear 22 is yieldingly held in engagement with the gear 13 by a helical spring 23, one end of which is secured to a screw 24 attached to the cylindrical bearing 20 and the other end of which is made fast to a pin 25 secured to the bottom of the inclined web 7. (See Figures 6 and 7.)

Fast on the outer end of each one of the shafts 9 and 21 between two discs 26, 26 preferably made of metal, is a resilient disc such as the rubber disc 27. These discs 27, 27 project a slight distance into a vertical channel 28 between two upper elongated members 29, 29 and two bottom pieces 30, 30 which form that channel. These members 29, 29 and end pieces 30, 30 which form the channel 28

are firmly secured to the outer face of the side support 3 of the casting, and are curved at their adjacent ends to conform to the contour of the discs 27, 27 which project between those ends a slight distance into the channel for a purpose soon to be described. (See Figure 1.)

Suitably secured upon the top of the side support 3 of the casting 1, are two rectangular metal plates 31, 31 which are recessed at their middle portions to form, when secured together by transverse screws 32, 32, a type receiving block. The middle recessed portions of the plates 31, 31 form together a central vertical groove 33 that extends down through the block which the plates form, to receive two type chutes 34, 34 whose upper ends are directly below two delivery chutes 35, 35 that receive type from a magazine not shown. At their lower ends the type chutes 34, 34 are spirally turned a sufficient amount to change the position of the type passing through them, 90 degrees before entering the channel 28 below. A multigraph type, which is a short thick type as shown in Figure 5, must be turned edgewise or the narrow way to pass through the chutes 34, 34 in the type receiving block without clogging it up.

Applied to the outer surfaces of the elongated members 29, 29 and the bottom pieces 30, 30 is an elongated strip such as the glass strip 36 to close the open side of the channel 28. The glass strip 36 is held in position against the members 29 and 30 by the outer ends of a yoke piece 37 through the central portion of which, and through an opposite hole in the casting, a screw 38 is inserted. This screw has an outer removable head 39 for pressure against the yoke piece 37 when the screw is drawn inwardly by a helical spring 40 surrounding its inner end between its fixed head and the inner surface of the side support 3 of the casting. The leg 41 of the yoke piece is turned at a right angle for pivotal attachment to a slotted block 42 secured to the side support 3. The yoke means just described will yieldingly hold the glass strip 36 over the channel 28. (See Figures 1 and 2.)

50 A type inserted in one of the spiral chutes 34 of the type receiving block, will be turned thereby 90° for proper entrance into the channel 28, through which it falls to the rubber discs 27, 27 where its descent is momentarily arrested. When the type is caught between the discs 27, 27, they are timed to be oscillated by the pulley means hereinbefore described to force it into a channel block for lateral ejection therefrom by means soon to be described. Referring to Figure 6, this channel block comprises a vertical member 43 secured at its lower end by a screw 44 to the side support 3, and a rectangular end member 45 secured by a screw 46 in a recessed portion of said side support. The in-

ner facing surfaces of these members 43 and 45 are recessed to conform to the contour of the type to permit the latter to be ejected laterally from the channel block which they form by an ejector mechanism now to be described.

The side support 3 is formed with a deep circular recess 47 for a crank disc 48 fast on the outer end of the pulley shaft 6. (See Figures 1 and 4.) Inclining upwardly from this circular recess 47 to the inner surface of the rectangular channel block member 45 is a pilot-block groove 49 which is also formed in said side support 3. A tapering recess 50 is formed in the side support 3 around the groove 49 to permit a free reciprocating movement therein of an ejector arm 51 having an inwardly projecting pin 52 that enters a hole in a pilot-block 53 slideable in the groove 49, and formed at its rear end with a hole through which a crank pin 54 on the disc 48 projects. (See Figure 1.)

When the disc 48 is rotated by the pulley means hereinbefore described, the curved end of the ejector arm 51 will be intermittently forced a sufficient distance between the channel block members 43 and 45 to eject through their recessed portions the type which the rubber discs 27, 27 have permitted to descend between them. When engaged by the outer curved end of the ejector arm 51, the type will be forced through the pilot recesses which fit its neck, in the channel block members 43 and 45, outwardly into a chase or individual tubes not shown.

The rubber discs 27, 27 are timed or synchronized so that they will be oscillated to pass a type between them on the rearward stroke of the ejector arm 51, so that when it is moved forward by the rotation of the disc 48, the type will be in proper position between the channel block members 43 and 45 for engagement by the curved outer end of the arm. The type will then be engaged by the ejector arm with sufficient force to eject it into the chase or other receptacle which receives it. The pilot-block 53 guides the outer end of the ejector arm 51 towards the type to be ejected, and during this movement of the ejector arm toward the type the discs 27, 27 will oscillate in a reverse direction and then remain stationary to prevent the descent of any other type until the one in the channel block below has been ejected. When a type passes between the rubber discs 27, 27, the outer one is free to be moved slightly outwardly against the tension of the spring 23 secured between the bearing 20 which carries the disc shaft 21 and the web 7, thereby making the engagement of the discs with the type a yielding one.

Adapted to be removably applied to the side support 3 of the casting, over the ejector arm 51 which it serves to retain on the crank pin 54 of the crank disc 48, is a cover 55.

The latter is secured to the side support 3 by thumb screws 56, 56. Formed in the inner surface of the cover 55 is an annular groove 57 around which the crank pin 54 is adapted to travel. The cover 55 also has on its inner surface a raised portion 58 adapted to fit snugly into the recess 50 of the side support 3 to prevent the ejector arm 51 from slipping off the crank pin 54, thus dispensing with a shoulder on that pin or other means for firmly securing the ejector arm to it. (See Figures 7 and 8.)

The rapidity with which the type may be ejected by my device is far greater than by a keyboard operator. The spiral chutes 34, 34 prevent the type, and more particularly that of the multigraph kind, from clogging the channels, while the rubber discs 27, 27 properly control the placement of the type 20 in the channel block below for ejection by the ejector arm 51.

Having described my invention, I claim:

1. In a device of the type described, the combination with a chute for the descent of type therethrough, of a type holder below said chute, means for laterally ejecting type from the holder, and rotatable means projecting into said chute, and synchronized with the movement of the ejecting means, to pass a type through the chute into the holder in the path of movement of the ejecting means.

2. In a device of the type described, the combination with a chute for the descent of type therethrough, of a type holder below said chute, means for laterally ejecting type from the holder, and a pair of oscillating rollers projecting into said chute, and synchronized with the movement of the ejecting means, to pass a type through the chute into the holder in the path of movement of the ejecting means.

3. In a device of the type described, the combination with a chute for the descent of type therethrough, of a type holder below said chute, an ejector arm adapted to enter said holder to laterally eject type therefrom, a pair of oscillating rollers projecting into the chute to pass type therethrough into the holder, and rotating means for reciprocating the ejector arm and oscillating the rollers in a synchronism to pass a type through the chute into the holder at the time the ejector arm is withdrawn therefrom.

4. In a device of the type described, the combination with a chute for the descent of type therethrough, of a type holder below said chute, an ejector arm adapted to enter said holder to laterally eject type therefrom, crank means for reciprocating said ejector arm, a pair of oscillating rollers projecting into the chute to pass type therethrough into the holder, crank means for oscillating said rollers, and rotating means for actuating the ejector arm crank means

and the roller crank means in a synchronism to pass a type through the chute into the holder at the time the ejector arm is withdrawn from it.

5. In a device of the type described, the combination with a chute for the descent of type therethrough, of a type holder below said chute, a shaft transverse to said type holder, crank means on the shaft in line with the type holder, an ejector arm secured to the crank means for movement into the type holder to eject type laterally from it, a pair of oppositely disposed discs projecting into said chute to pass type therethrough into the type holder, transverse shafts on which said discs are fast, a gear on one of said shafts in mesh with a gear on the other shaft, a drive pulley on the ejector arm shaft, and crank means operatively connected between the pulley and one of said gears to oscillate the discs in synchronism with the movement of the ejector arm by the crank means on the first shaft to pass a type through the chute into the holder at the time the ejector arm is withdrawn from it.

6. In a device of the type described, the combination with a chute for the descent of type therethrough, of a type holder below said chute, a pair of oppositely disposed discs projecting into said chute to pass type therethrough into the type holder, a stationary transverse shaft upon which one of said discs is mounted and a swinging transverse shaft upon which the other one of said discs is mounted, and resilient means for drawing the swinging shaft toward the stationary shaft to maintain a yielding engagement between the discs and the type which they pass into the type holder.

7. In a device of the type described, the combination with a chute for the descent of type therethrough, of a type holder below said chute, crank means in line with said type holder, a side support for said crank means, said support formed with a groove leading from the crank means to the type holder, a pilot block movable in said groove, and an ejector arm pivotally secured to the crank means and the pilot block for movement into the type holder after a type has dropped therein from the chute, to eject said type laterally therefrom.

8. In a device of the type described, the combination with a vertical web support, of a type holder secured at one end thereof, said support having a recessed portion in one side leading to the type holder, a crank disc rotatable in said recessed portion of the support, an outwardly projecting crank pin on said disc, an ejector arm movable into said type holder to eject a type therefrom and formed at its inner end with a hole through which said crank pin projects, and a cover applied to said support over its recessed portion and having an annular groove

formed in its inner surface to permit the free rotary movement of the crank pin therein for the purpose specified.

9. In a device of the type described, the combination with a vertical type receiving member, of type ejecting means below the latter, and spiral passages in said receiving member to turn the type to edgewise positions for descent through the latter to the type ejecting means below.

10. In a device of the type described, the

combination with a vertical chute, of ejecting means below the latter, a channel block mounted above said chute, and spiral passages in said channel block to turn the type 15 descending therethrough an angle of substantially 90° for a free entrance into the chute below.

In witness whereof I have hereunto set my hand this 25th day of April, 1925.

FRANK H. POEPPELMEIER.
